CLAIM

We claim the ornamental design for a gaming machine display, as shown and described.

DESCRIPTION

FIG. 1 is a front perspective view of a gaming machine display showing our new design;

FIG. 2 is a front view of the gaming machine display shown in FIG. 1;

FIG. 3 is a back view of the gaming machine display shown in FIG. 1;

FIG. 4 is a left side view of the gaming machine display shown in FIG. 1;

FIG. 5 is a right side view of the gaming machine display shown in FIG. 1; and,

FIG. 6 is a top view of the gaming machine display shown in FIG. 1.

The showing of broken lines are included for the purpose of illustrating environmental structure and forms no part of the claimed design.

1 Claim, 6 Drawing Sheets
